UNITED STATES PATENT OFFICE.

HANSON P. TENANT, OF DUBLIN, ASSIGNOR TO HORACE R. ALLEN, OF INDIANAPOLIS, INDIANA.

EJECTOR OR INJECTOR.

SPECIFICATION forming part of Letters Patent No. 351,005, dated October 19, 1886.

Application filed March 10, 1886. Serial No. 194,691. (Model.)

To all whom it may concern:

Be it known that I, HANSON P. TENANT, a citizen of the United States, residing at Dublin, in the county of Wayne and State of Indiana, have invented certain new and useful Improvements in Ejectors or Injectors; and I do hereby declare the following to be a full, clear, and exact description of the invention, such as will enable others skilled in the art to which it appertains to make and use the same.

The object of this invention is to produce powerful and direct ejection or injection of liquid.

The invention consists, first, in an ejection or injection device, in which a partial diaphragm insures division of the liquid and simultaneous and equal delivery of the same on both sides or all around the nozzle. Furthermore, in a straight nozzle or one of substantially equal diameter in the passage from the liquid-chamber, and centrally placed therein, whereby the quantity of liquid about the nozzle is rendered equal on all sides, and, falling in front of the nozzle centrally, is directly projected by the steam or other pressure employed without swirl. Furthermore, in the combination, with a straight injector-pipe and liquid passage in which it is centrally placed, of a liquid chamber or reservoir communicating directly with the passage, whereby the liquid flows equally to such passage; and, finally, in means for adjusting the degree of projection of the nozzle into the liquid-passage for varying conditions of use.

In the accompanying drawings, forming part of this specification, and in which like letters of reference indicate corresponding parts, Figure 1 is a longitudinal section of a device embodying my invention. Fig. 2 is a cross-section of the same, showing the bridge or partial diaphragm. Fig. 3 is a detail view showing means of adjusting the nozzle for varying conditions of use.

Referring to the drawings, A is the shell, upon or in which all the other parts are arranged.

B is the inlet for liquid, which may be water coming direct from a well.

C is the steam or fluid pressure pipe, which is straight and central within the liquid-pas-

sage D, and has its outlet-opening narrowed all around equally and near the eduction-passage E.

F is the inlet for steam or other fluid under pressure, which may connect with the interior 55 of a boiler or other receptacle to be filled with liquid, and whence the initial power is derived; or it may be connected with any other source of steam or other suitable pressure independent of supply of liquid thereto by the 60 ejection or injection device to which it is attached.

G is a bridge or partial diaphragm in the liquid-inlet pipe, duct, or conduit B, attached on two sides to the interior of such conduit, and 65 leaving on the other sides, about at right angles thereto, or laterally, water-ways or liquid-passages g g, which may give to the device an expansion or swell, as shown. These ways lead directly to the liquid-chamber H, which 70 forms a large reservoir for the even supply of liquid to the passage D, with which in turn it freely communicates. The reservoir H forms an equalizing-chamber for the even and uniform supply of liquid to the front of the nozzle. The purpose of the bridge is to supply 75 the liquid equally and uniformly, and keep it from striking directly upon the pipe or nozzle C. It divides the stream into two parts, and brings each part to the nozzle simultaneously. 80 The pipe C passes into the interior of the shell through a suitable opening in the end thereof, and is provided with the outward-projecting flange e, which prevents it from being inserted farther into the shell than is proper, and 85 is held rigidly in position by the nut or screw-cap I. The steam-connection K is, it will be seen, made on the extreme outer end of the pipe C, and there need be no valve in the pipe to rust or get out of order and untrue by reason of the long connection, which must usually be had with such valves to operate them.

The device, though applicable to any purpose for which an ejector or injector can be used, was originally intended as an ejector for 95 deep wells; but when an adjustment is desired for shallow wells the nut I may be unscrewed and slipped back on the nozzle, and a copper or other suitable washer, L, be inserted between the flange e and the shell A. This 100

washer is split on one side and opened to slide around the pipe C; or the pipe may be taken out and the washer be slipped on whole.

The invention presents a very effective 5 ejector or injector of simple construction. The force-pipe being straight and centrally placed, the supply of liquid is equal on all sides and falls right in front of the nozzle, so that the steam or other forcing fluid 10 strikes and mixes with it equally and centrally, whereby any lateral current or swirl is avoided. The large reservoir acts as an equalizing-chamber, insuring constantly uniform supply of liquid, and this is aided by the 15 bridge. A full body of liquid is constantly carried through by the steam, and there is no possibility of passage of air.

Having thus fully described my invention, what I claim as new, and desire to secure by 20 Letters Patent, is—

1. The combination, in an ejector or injector, of a casing provided with an inlet, a pipe through which the fluid under pressure passes through the casing at right angles to the 25 inlet, and a bridge formed upon the inlet in

such manner as to divide the current of fluid entering the inlet-opening, substantially as described.

2. The combination, in an ejector or injector, of the casing provided with the inlet-opening, the steam-pipe provided with a reduced end, and the bridge formed upon the inlet at the point at which the liquid impinges, the steam-pipe passing through the casing at right angles to the inlet-opening, substantially 35 as described.

3. The combination, in an ejector or injector, of a casing provided with suitable inlet and outlet, a steam-pipe passing through the casing at right angles to the inlet, a chamber surrounding the steam-pipe, and a bridge formed upon the inlet, all arranged substantially as described, to prevent unnecessary agitation of the fluid to be injected or ejected. 40

In testimony whereof I affix my signature in 45 presence of two witnesses.

HANSON P. TENANT.
